United States Patent Office

Des. 181,632
Patented Dec. 10, 1957

181,632

PERFUME BOTTLE STAND OR SIMILAR ARTICLE

Eric de Kolb, New York, N. Y., assignor to Coty, Inc.,
New York, N. Y., a corporation of Delaware

Application March 4, 1957, Serial No. 45,053

Term of patent 14 years

(Cl. D86—10)

Fig. 1.

Fig. 2.

Fig. 3.

Fig. 1 is a top plan view of a perfume bottle stand or similar article showing my new design;

The broken line showing of the bottle is for illustrative purposes only.

I claim:

The ornamental design for a perfume bottle stand or similar article, substantially as shown and described.
